ABSTRACT OF THE DISCLOSURE

The disclosure concerns a mould for casting metal, the corners of the mould being obtuse angled and coolant flow means being provided on the exterior faces of the mould sides and corners.

This invention is concerned with improvements in and relating to moulds for casting and more particularly to casting moulds for use in conjunction with electroslag refining equipment.

According to one aspect of this invention there is provided a mould for casting metal comprising a plurality of side walls interconnected by corner plates to provide obtuse angle corners in the cast product and means for delivering a flow of coolant down the exterior faces of the side walls and a flow of coolant along the outer faces of the corner panels.

In order that the present invention may be well understood there will now be described two embodiments, given by way of example only, reference being had to the accompanying drawings in which:

FIG. 1 is a part sectional plan view on the line B—B of FIG. 2;

FIG. 2 is a part sectional elevation on the line A—A of FIG. 1;

FIG. 3 is a transverse cross section of the walls of another embodiment of mould, and

FIG. 4 is a fragmentary elevation of one major wall of the mould of FIG. 3.

The mould, which is of conductive material, is here open ended and the cavity is defined by four walls 1 interconnected by corner plates 2 so that the transverse section of the mould and hence the cast product has obtuse angle corners for example 135°. The mould unit at the lower end is surrounded by a trough 3 and at the upper end by a header 4 which has inwardly directed outlet apertures 5 to direct coolant, generally water, on to the exterior of the walls 1. The corner plates each in part define a coolant feed passage to pass coolant to the header from one of a pair of coolant inlet branches 6 coupled to an inlet pipe 7. An outlet 8 is coupled to the trough. In a modification of the mould shown in FIGS. 1 and 2, the walls diverge in the downward direction of the mould so that the corner plates are trapezoidal.

In operation the mould is positioned on a suitable base and a slag powder is fed into the mould. An electrode of metal to be refined is fed down into the slag, and a conductive path is established through the electrode, slag and the base or a second electrode. This causes slag to melt and then the electrode to melt. The molten metal passes down through the slag and forms a pool in the mould above the base.

As the metal is removed from the electrode the slag is progressively displaced upwards by the metal accumulating in the mould, though a slag skin does form against the surface of the mould due to the chilling action of the mould wall. Freezing takes place progressively and at any time there is a comparatively small molten metal

2

pool. On completion, the electrode is withdrawn and freezing continues until complete. The mould is then withdrawn from the casting.

Referring to FIGS. 3 and 4 there is shown a simplified embodiment of mould in which the coolant feed passages are replaced by a pair of spaced fins 9', each projecting outward from the junction of a wall 1' and a corner plate 2'. A header 4' is provided surrounding the upper part of the mould with apertures as before for directing a spray on to the walls 1' and additional apertures for directing a spray on to the corner panels. The additional apertures are arranged, as by being of larger diameter, to give an increased flow of coolant at the corner panels and the apertures nearest the fins are angled not only to direct the coolant toward the corner panel face but also toward the adjacent fin to direct coolant into the angle defined by the fin and corner panel. The arrows 10 of FIG. 4 diagrammatically show the directions of the coolant flow from the header at a corner panel.

The above described moulds provide these advantages:

(1) Because the mould has a taper, and because the four wide-face panels are rectangular, the four corner panels are trapezoidal. These corner panels would be difficult to cool by direct spraying, especially if a large mould taper was employed, due to the fact that the falling curtain of water would not be wide enough at its base to cover the full width of the corner panels.

(2) It would be difficult to cool square tapering ingots having 90° or radiused corners by spray cooling. Corner cooling is facilitated by making the mould corners flat and by ensuring a large flow of water in this region. The method also ensures adequate cooling of the vertical corner welds where increased wall thickness gives slower heat transfer.

(3) By cutting off the ingot mould corners and by virtue of the thicker ingot slag skin produced at the corners due to the increased cooling, an ingot free from a sharp corner is produced. This minimizes any tendency towards segregation of elements in the casting at the columnar crystal junction within the corners.

We claim:

1. A relatively thin walled mould for casting metal comprising:

(a) a plurality of relatively wide side walls;

(b) relatively narrow corner plates interconnecting said side walls to provide obtuse angle corners in the cast product;

(c) means for delivering a flow of coolant down the exterior faces of said side walls and for delivering a flow of coolant along the outer faces of said corner plates, said means including a spray header;

(d) means for conveying coolant to said means (c); and

(e) means defining corner plate coolant flow passages located at each junction of a side wall and a corner plate for restraining the coolant flow over said corner plates from passing onto said side walls.

2. A mould according to claim 1 in which each corner plate is trapezoidal and of increasing width in the direction of the end which will be lowermost and said side walls are rectangular.

3. A relatively thin walled mould for casting metal comprising

(a) a plurality of relatively wide side walls;

(b) relatively narrow corner plates interconnecting said side walls to provide obtuse angle corners in the cast product;

(c) spray header means having coolant discharge apertures for delivering a flow of coolant down the exterior faces of said side walls; and

(d) means cooperating with said corner plates to define coolant feed passages for feeding coolant up said corner plates to said spray header means.

4. A mould according to claim 1, in which said restraining means comprises an outwardly projecting fin at each junction between a side wall and a corner plate and in which said means for delivering a flow of coolant along the outer faces of said corner plates comprises portions of said spray header associated with the corner plates, each said portion having discharge apertures, at least some of which are directed towards the corner plate and at least some of which are arranged to direct coolant into the angles formed between the corner plate and the associated fins.

5. A mould according to claim 3 in which said spray header means is a spray header extending about the uppermost part of said mould with which header each passage is connected.

6. A mould according to claim 4 in which said spray header extends about the uppermost part of the mould and has further portions associated with the side walls, said further portions having additional coolant discharge apertures for delivering the flow of coolant down the exterior faces of the side walls, at least some of the discharge apertures in the corner plate portions being of a larger diameter than said additional apertures.

7. A mould according to claim 1 in which said means

for delivering a flow of coolant delivers a greater flow along the outer faces of the corner plates than down the exterior faces of the side walls.

8. A mould according to claim 2 in which said means for delivering a flow of coolant delivers a greater flow along the outer faces of the corner plates than down the exterior faces of the side walls.
